Ino. Heily.
Harvester Cutter.

No. 14790

Patented April 29, 1856

FIG. I

FIG. II

FIG. III

FIG. IV

FIG. V

UNITED STATES PATENT OFFICE.

JOHN REILY, OF HEART PRAIRIE, WISCONSIN.

IMPROVEMENT IN HARVESTER-FINGERS.

Specification forming part of Letters Patent No. 14,790, dated April 29, 1856.

To all whom it may concern:

Be it known that I, JOHN REILY, of Heart Prairie, in the county of Walworth and State of Wisconsin, have invented certain new and useful Improvements in Cutting Apparatus of Reaping and Mowing Machines, of which the following is a full, clear, and exact description, reference being had to the accompanying drawings of the same, in which—

Figure 1 represents a side elevation of the tooth, showing in red lines the case-hardened part; Fig. 2, a cross-section of the same; Fig. 3, a plan of my improved cutter; Fig. 4, a front view of the same, showing the sickle-eye secured to one end in red lines and the other in black; and Fig. 5, a modification of my improved cutter, the rear end of the sections being shown in dotted lines.

The first branch of my invention relates to the fingers that gather the grain and support it while being cut by the sickle, and which have heretofore been made of cast or wrought iron; but when made of such material it has been found that they wear rapidly away under the action of the steel cutters, from the fact of the latter being much harder than the iron of the fingers, the friction thus produced requiring a much greater amount of power to drive the knife than would otherwise be sufficient if the metals were of the same hardness. It therefore becomes an object of importance to provide a tooth that would possess the requisite degree of hardness without materially increasing the cost of its manufacture. There is also another reason that renders it desirable to substitute a hardened tooth for those in common use—to wit, that the friction produced by the abrasion of the softer metal necessarily dulls or blunts the cutting-edges of the knife, which causes it rather to tear or break the stalks asunder than cut it, in this way requiring more power to operate the knife, the combined effect of which is to cause the cutter-bar to twist or break and otherwise impair the efficiency of the machine by straining its operative parts.

To supply a tooth that would remedy these defects without materially adding to its cost is one of the features of my present invention and it consists in "case-hardening" that part of the tooth on which the knife rests and works.

I am aware that steel plates have heretofore been inserted into the upper side of the fingers

to act as stationary cutters; but to these I lay no claim, as they are at once costly and liable to get out of order.

The tooth *a* is first forged out of a piece of wrought-iron into the proper shape and proportion, and that part of it on which the knife rests filed perfectly smooth and level, and, if necessary, polished. It is then put into the fire and heated to a dull-red heat, when it is withdrawn and a portion of powdered prussiate of potash spread evenly over it or rubbed in a lump over that part desired to be hardened. In this state it is again submitted to the action of the fire, and then immersed in cold water, when the process is complete. The part thus hardened possesses to a certain extent the properties of steel, and, having been previously polished or smoothed, causes far less friction and abrasion as the knife is operated than when the old fingers are used, thus requiring much less power to drive it; and, as the two (the finger and knife) possess about the same degree of hardness, the wear on their surfaces will be about equal. The wear on the knife, being on its under side, will act as a sharpener, instead of dulling its edge, as heretofore; and the edge thus ground on the upper side of the tooth by the action of the knife will act itself as a cutter on the principle of the shear. To still further increase this tendency, the under side of the tooth, immediately below the knife, may be beveled off, so as to bring its upper side to an edge, as seen at Fig. 2. The hardening process may be effected by any of the well-known modes for such purposes.

The second branch of my invention relates to the knife, which has hitherto been constructed as a single-sickled knife for reaping grain or as a single plane or smooth edged knife for mowing; but when made in either of these ways a machine intended to mow as well as to reap, is compelled to carry both kinds, or else to use but the one and lose the advantages of the other, the one being preferable in reaping and the other in mowing. The object of my invention is to combine the two in one at a cost little exceeding that of a single knife. A knife constructed on this principle is necessarily a little heavy; but by using a steel bar to rivet them to, (and which has been commonly used for this purpose by those whose knives from their peculiar construction are heavy, (instead of an iron one, its weight will

be materially lessened and the effect produced still more so when used in connection with my case-hardened teeth.

On the bar *c*, which may either be of steel or iron, are riveted the sections *d*, having one side, *e*, sickled for cutting of grain and the other side, *f*, smooth for mowing, all the sickled edges being secured and projecting over the same side of the bar, while the plain edges project over the other, they being so secured that their opposite points shall project equally, or nearly so, on each side of the bar. It is also desirable that the apex of the angles formed by the junction of the sections should not terminate at the edge of the bar, but that they should meet at a short distance from it, as shown in Fig. 5. In making these sections it is not necessary that they should be formed by the projecting points of a lozenge-shaped blade, as the blades of each side of the knife may be formed of a separate series of sections, as seen at Fig. 5, which in some respects is preferable, inasmuch as the cutting-edge of a blade on one side may be rendered unfit for use, when it may be removed and another substituted in its stead, whereas in the other case a whole lozenge forming a cutting-edge on both sides must be sacrificed; and, again, the whole knife may be cut out of a single sheet of steel; but this I do not deem an advisable plan, as the

destruction of one of its cutting-edges may render the whole worthless.

On the end of the bar *c* is secured a sickle-eye, *g*, by means of set-screws *h*, this being made removable, so that on turning or changing the sickled edge round to the rear for the purpose of using the smooth-edged one it may be removed from the end suited to the former and secured to that adapted to the working of the latter, both ends of the bar having holes *i* pierced in them for the reception of the set-screws *h*, that secure the sickle-eye to the bar. On the outer extremity of the sickle-eye is a mortise, *t*, through which the bolt that connects it with the pitman-rod passes, and by which motion is communicated to the knife from the driving-gear of the machine.

Having thus described my invention, what I claim as new, and desire to secure by Letters Patent, is—

Hardening that part of the tooth on which the knife works, for the purposes substantially as herein set forth.

In testimony whereof I have hereunto set my hand in presence of two subscribing witnesses.

JOHN REILLY.
